CLAIM

What is claimed is the ornamental design for a bumper for a vehicle, as shown and described.

DESCRIPTION

This application is an application for reissue of U.S. Design Pat. No. D. 826,115, which issued on Aug. 21, 2018, from U.S. Design application Ser. No. 29/590,944, filed on Jan. 13, 2017, the contents of which are entirely incorporated by reference herein.

FIG. 1 illustrates a perspective view of a new and ornamental bumper for a vehicle, according to one embodiment;

FIG. 2 illustrates a front view thereof;

FIG. 3 illustrates a back view thereof;

FIG. 4 illustrates a left-side view thereof;

FIG. 5 illustrates a right-side view thereof;

FIG. 6 illustrates a top view thereof; and,

FIG. 7 illustrates a bottom view thereof.

Broken lines in the drawings depict portions of the bumper for a vehicle that form no part of the claimed design.

1 Claim, 6 Drawing Sheets

Matter enclosed in heavy brackets [ ] appears in the original patent but forms no part of this reissue; matter printed in italics indicates the additions made by reissue.
